UNITED STATES PATENT OFFICE.

JOHN LAIRD, OF BELFAST, IRELAND, ASSIGNOR OF TWO-THIRDS TO THE HOPE STREET FACTORY, LIMITED, OF SAME PLACE.

PRESSER-CLAMP FOR BUTTONHOLE-SEWING MACHINES.

SPECIFICATION forming part of Letters Patent No. 606,423, dated June 28, 1898.

Application filed September 29, 1896. Serial No. 607,324. (No model.)

To all whom it may concern:

Be it known that I, JOHN LAIRD, a subject of the Queen of Great Britain and Ireland, residing at 4 Hibernia place, Lisburn road, Belfast, Ireland, have invented an Improved Presser-Clamp for Buttonhole-Sewing Machines, of which the following is a specification.

The object of my invention is to enable the presser-clamp of a buttonhole-sewing machine to move more freely than has heretofore been the case, both lengthwise and laterally, and bear with even pressure on material of irregular thickness—as, for instance, in the case of shirt parts, where there is an extra thickness of material near the front collar-button-hole of a shirt-front at the point where the collar or collar-band is attached to the front, or similarly in a cuff, where at the stud-holes the interlining is cut away and thus thinned to allow the stud to be more easily inserted. With this view I hinge the presser-clamp to a frame, said frame being hinged to the clamp-plate in such a manner that the presser-clamp, with the frame, is free to vibrate in one direction or plane within the clamp-plate, while at the same time the presser-clamp is free to vibrate within the frame in a direction or plane at right angles to the vibration of the frame within the clamp-plate.

I will now proceed to describe, with reference to the accompanying drawings, the manner in which my invention is to be performed.

Figure 1 is a plan of the clamp-plate, showing the presser-clamp and frame in place as applied, for example, to a buttonhole-sewing machine described in my United States Patent No. 562,003, of June 16, 1896. Fig. 2 is a section on the line 2 2, Fig. 1. Fig. 3 is a section on the line 3 3, Fig. 1.

The presser-clamp *u* is provided on the upper side with a small lug *u'* at each end and equidistant from either side. These lugs are drilled to receive hinge-pins *u²*, secured in corresponding lugs *u³* on the upper side of a frame *u⁴*, which carries and surrounds the presser-clamp *u*. Sufficient clearance only is left between the sides of the presser-clamp *u* and the frame *u⁴* to allow the presser-clamp a limited vibration on the hinge-pins *u²*. On

the upper side of the frame *u⁴*, at the sides of the same and equidistant from either end, are two other lugs *u⁵*, which are drilled in the same longitudinal plane as the hinge-pins *u²* to receive hinge-pins *u⁶*, secured to the upper side of the clamp-plate *U* or to lugs *u⁷* thereon. Sufficient clearance only is left between the ends of the frame *u⁴* and the clamp-plate *U* to allow the frame a limited vibration on the hinge-pins *u⁶* on the clamp-plate.

The clamp-plate may be attached to the machine in the ordinary way or in any convenient manner. The same result may be obtained by fitting the presser-clamp *u* with hinge-pins at each side instead of at each end within the frame *u⁴*, while the frame *u⁴* is fitted with hinge-pins at each end instead of at each side within the clamp-plate *U*.

What I claim, and desire to secure by Letters Patent, is—

1. A sewing-machine clamp-plate, a frame journaled in an opening thereof and having a limited movement on its journals, and a clamping-foot journaled in said frame and having its journals in the same horizontal plane but at right angles to the frame-journals, said clamping-foot having likewise a limited movement on its said journals, for the purpose set forth.

2. A sewing-machine clamp-plate, a four-sided open frame pivoted at opposite ends in an opening thereof and a four-sided clamping frame or foot pivoted at two opposite sides in the opening of the first-mentioned frame at right angles to its pivots, all the pivot-centers being in the same horizontal plane and both frames having limited movement, for the purpose set forth.

3. A sewing-machine clamp-plate, a frame pivoted in an opening thereof and projecting slightly below said plate and a clamping-frame pivoted at right angles to, and within the first-mentioned frame and projecting slightly below said frame, all the pivots being in the same plane and the frames having limited motion.

JOHN LAIRD.
